UNITED STATES PATENT OFFICE.

MATTHEW C. DAY, OF PROVIDENCE, RHODE ISLAND, ASSIGNOR TO J. B. & S. M. KNOWLES COMPANY, OF PROVIDENCE, RHODE ISLAND.

DESIGN FOR A HANDLE FOR PAPER-KNIVES OR SIMILAR ARTICLES.

SPECIFICATION forming part of Design No. 36,525, dated August 25, 1903.

Application filed August 1, 1903. Serial No. 167,952. Term of patent 7 years.

To all whom it may concern:

Be it known that I, MATTHEW C. DAY, a citizen of the United States, residing at Providence, in the county of Providence and State of Rhode Island, have invented a new, original, and ornamental Design for the Handle of a Paper-Knife or Similar Article, reference being had to the accompanying drawing.

The figure in the drawing shows the obverse side of a paper-knife, on the handle of which is my design.

What I claim as new, and desire to secure by Letters Patent, is—

The ornamental design for the handle of a paper-knife or similar article as shown.

In testimony whereof I have signed my name to this specification in the presence of two subscribing witnesses.

MATTHEW C. DAY.
